UNITED STATES PATENT OFFICE.

MORGAN PENNYBACKER, OF WASHINGTON, DISTRICT OF COLUMBIA, AS-
SIGNOR OF ONE-HALF TO ALBERT F. KINGSLEY, OF SAME PLACE.

NUT-LOCK.

SPECIFICATION forming part of Letters Patent No. 398,795, dated February 26, 1889.

Application filed November 20, 1888. Serial No. 291,327. (No model.)

To all whom it may concern:

Be it known that I, MORGAN PENNYBACKER, a resident of Washington, in the District of Columbia, have invented certain new and useful Improvements in Nut-Locks; and I do hereby declare the following to be a full, clear, and exact description of the invention, such as will enable others skilled in the art to which it pertains to make and use the same.

10 My invention relates to an improvement in nut-locks; and it consists in the peculiar construction and combination of devices that will be more fully set forth hereinafter, and particularly pointed out in the claim.

15 In the accompanying drawings, Figure 1 is an axial sectional view showing the nut locked on the bolt. Fig. 2 is a perspective view showing the nut in position upon the bolt before being locked thereto.

20 A represents the bolt, having its threaded portion provided on diametrically-opposite sides with grooves B.

C represents the nut, which is of the usual construction.

25 D represents a washer having a central opening of sufficient diameter to receive the bolt and to slip freely thereon. Secured to the lower side of the washer are wires E, which are bent outward at right angles to the washer 30 and project therefrom, the said wires being arranged within the radius of the opening in the washer and adapted to fit and slide in the grooves of the bolt when the washer is placed thereon. The said grooves are of sufficient depth to enable the wires to clear the threaded opening of the nut, so that the latter may be

35 screwed home on the bolt in the usual manner. In order to lock the nut, it is only necessary to bend the projecting ends of the 40 wires outward on the face of the nut and over the sides thereof, as shown in Fig. 1, and

when thus secured the nut cannot become unscrewed by any amount of shaking to which it may be subjected.

No claim is made herein to the bolt having 45 the grooves or key-seats, in combination with the wires to fit in said grooves and then bent on the face of the nut, as I am aware that such construction is not broadly novel. It has been heretofore proposed to provide such a 50 bolt with a transverse opening connecting the inner ends of the grooves, and to provide a substantially U-shaped wire to fit in said opening and grooves. Such construction is 55 objectionable for the reason that the transverse opening increases the expense of the bolt, and also weakens it. I obviate these objections by providing the washer with the wires to fit the grooves, thus dispensing entirely with the opening in the bolt. More- 60 over, my improved nut-locking device possesses advantages over the construction hereinbefore disclaimed, inasmuch as it can be much more readily and quickly applied to a 65 bolt and nut.

Having thus set forth and particularly described my invention, I claim—

The combination, with the bolt having the longitudinal grooves and the nut, of the washer adapted to slip freely on the bolt, and 70 having the wires to fit in the grooves, said wires being adapted to be bent outward over the face and sides of the nut to lock the latter, substantially as described.

In testimony whereof I have signed this 75 specification in the presence of two subscribing witnesses.

MORGAN PENNYBACKER.
